No. 761,817.

PATENTED JUNE 7, 1904.

S. C. BURRIS.

ADJUSTABLE MITER BOX.
APPLICATION FILED FEB. 19, 1903.

NO MODEL.

UNITED STATES PATENT OFFICE.

SAMUEL CYRUS BURRIS, OF SEATTLE, WASHINGTON.

ADJUSTABLE MITER-BOX.

SPECIFICATION forming part of Letters Patent No. 761,817, dated June 7, 1904.

Application filed February 19, 1903. Serial No. 144,157. (No model.)

To all whom it may concern:

Be it known that I, SAMUEL CYRUS BURRIS, a citizen of the Dominion of Canada, and a resident of the city of Seattle, in the county of King and State of Washington, have invented certain new and useful Improvements in Adjustable Miter-Boxes, of which the following is a specification.

My invention relates to improvements in adjustable miter-boxes, and has special reference to a device of this class in which both the saw-guides and work-guides are adjustable.

Among numerous objects attained by this invention and readily understood from the following specification and accompanying drawings, included as a part thereof, is the production of a simplified and efficient miter-box embodying essential features of adaptability, utility, and adjustability, which widens the scope of operation and facilitates the cutting of simple and complex bevel or miter joints.

The above-mentioned and numerous other desirable objects are attained by the constructions, combinations, and arrangements of parts as disclosed on the drawings, set forth in this specification, and succinctly pointed out in the appended claims.

With reference to the drawings filed here-with and bearing like reference characters for corresponding parts throughout, Figure 1 is a view in perspective of my improved miter-box, showing the saw-frame and work-guides in adjusted position to make a cut for a complex joint. Fig. 2 is a view in end elevation of the device, showing one of the carrier-guides of the saw-frame in broken section and the base of the device disclosed in transverse section on line 2-2 of Fig. 1 viewed as the arrows indicate. Fig. 3 is a view in perspective of one of the saw-carriers removed from the device. Fig. 4 is a view in transverse sections of one of the carrier-guides of the saw-frame and shows the carrier therein and a portion of a saw in relative position and like section, and Fig. 5 is a view in perspective of the adjustable guide-block for the saw-frame detached.

This invention includes a box-frame which comprises a suitable rectangular base-plate 11

and an adjustable box-frame 12, consisting of a bottom section and a side section, the former section being arranged for tilting from the horizontal and preferably composed of a plurality of work-guides, as 14, set parallel to each other at the desired separation and arranged for vertical adjustment at one end, so that the bottom section thus formed can be conveniently tilted from the horizontal. In the present embodiment the said side section 60 is suitably arranged for vertical movement and is preferably composed of a plurality of perpendicular work-guides, as 15, set in alignment and movably supported for vertical adjustment, and as now considered a bottom 65 work-guide 14 is suitably hinged at one end to each of these side work-guides with the free end resting upon base 11 by means of a horizontally-disposed pivot, as 16, secured in the upright substantially midway its length, so 70 that these bottom guides can be conveniently adjusted or tilted to the desired angle by moving the side guides vertically and the upper end portions of these uprights made to serve as the side guides for the work. As now considered these side guides comprise rectangular posts each of which is formed with a longitudinally-disposed guideway, as 17, arranged in opposite side surfaces and adapted to slidably engage suitable oppositely-disposed L-shaped guides, as 18, which are secured to a bracket, as 19, at suitable points to slidably support said posts at the desired separation. This bracket 19 is preferably removably secured at one side edge of the base-plate 11 and 80 consists of a narrow section of plate metal of considerable length and formed with oppositely-disposed laterally-projecting lugs or ears, as 20, adjacent each end arranged at suitable separation to receive the base-plate 90 11 snugly therebetween, and a set-screw or the like, as 21, is seated in each of the bottom lugs in a transversely-disposed screw-threaded aperture, so that the bracket can be conveniently secured in place by tightening these 95 screws against the under surface of the base-plate, Fig. 2.

As now considered the side guides are adjusted or moved vertically by means of suitable racks 22 and pinions 23, the former be-

ing arranged on the outer side face of the lower half of the guides and the latter fixedly mounted in mesh with respective racks on a horizontally-disposed shaft, as 24, rotatably supported from the bracket 19 by suitable bearings 25, which are secured to the outer side surface thereof. This shaft is conveniently rotated in any suitable manner to raise or lower the side guides simultaneously, as 10 by means of a pawl-and-ratchet contrivance 26 of any desired or ordinary construction, and graduation-marks, as 27, Fig. 2, are arranged along one edge of one of the side guides, by which the angle at which the bottom guides rest can be determined and the proper adjustment of these guides to support the work for a predetermined cut thereby facilitated.

Embodying with the box proper is a pivotally-mounted saw-frame, as 28, which is disposed substantially midway the length of the box and suitably mounted for adjustment in both a vertical and horizontal arc, so that the saw can be thereby adjusted in two planes. 20 As now considered this frame comprises a horizontally-disposed base 29, preferably composed of a round rod, and a vertically-disposed carrier-guide, as 30, secured to said base adjacent each end thereof and preferably consisting of a suitable head, as 31, having a bore of suitable size to receive said base-rod, and a tubular stem, as 32, extending upwardly from said head and having longitudinally-disposed blade-receiving slots 33 at diametrically opposite points in the wall. The base of this saw-frame is suitably rotatably mounted for adjustment throughout a vertical arc by means of a bearing or box, as 34, which is conveniently pivotally mounted on the bracket 19, so as to turn on a vertical axis, and thereby allow the frame to be swung or adjusted throughout a horizontal arc, and as now considered this bearing comprises an eye of suitable size to receive the base and formed with 30 a downwardly-extending stem rotatably fitting in a vertically-disposed aperture formed in a lug, as 35, fixed to bracket 19, and a set-screw, as 36, is engaged in a suitable screw-threaded aperture in the wall of said lug, by 40 which said bearing is conveniently secured in horizontally-adjusted positions, and a set-screw, as 37, is engaged in the wall of said eye to secure the frame in vertically-adjusted positions. 50 Adjacent the free end of the saw-frame a suitable steadyer, as a movably-mounted guide-block 38, is conveniently arranged to carry said end of the frame, and as now considered this steadyer is mounted on a suitable horizontally-disposed way, as 39, consisting of a flat bar having grooves along the side edges, and this way is secured parallel with the bracket 19 at suitable separation therefrom by means of bars 40, disposed transversely 60 the base-plate 11 adjacent each end and se-

cured to the said bracket and the said way. The guide-block 38 as now considered includes a base 41, formed with a downwardly-projecting L-shaped guide, as 42, on each side edge, arranged to engage in the grooves of the way 39, and a bearing, as 43, for the base-rod 29 of the saw-frame, which is rotatably mounted on said base 41. The way 39, on which this steadyer is mounted, is provided with suitable graduation-marks, as 45, arranged radially with the axis of rotation of the bearing 34 and suitably disposed to indicate the proper position of the steadyer to bring the saw-frame to a desired horizontal adjustment, and a set-screw 46 is arranged in the base 41 of the steadyer in a suitable position to impinge upon the way 39 when properly turned, and thereby conveniently clamp the steadyer in adjusted positions.

In the present instance a suitable saw-carrier, as 46, is slidably engaged in the bore of each of the carrier-guides 32, and as now considered these carriers each comprise oppositely-disposed parallel prongs 47, which are approximately equal in length to the width of the saw-blade and are connected together at one end and formed with inwardly-projecting toes, as 48, at the free ends, which stand at suitable separation to receive the blade of the saw, as 49, snugly but freely therebetween and serve to prevent the saw from buckling in the cut. Adjacent the upper end of each of these prongs an inwardly-projecting guide-pin, as 50, is suitably secured on the inner surface thereof, and the blade of the saw 49 is preferably formed with a longitudinally-disposed groove, as 51, disposed adjacent the top edge in one side surface and adapted to slidably receive the end portion of one of the guide-pins 50, so that the saw will be thereby supported on the carrier. These carriers are preferably rendered substantially rectangular, as viewed in cross-section, and the bores of the carrier-guides are shaped in conformity therewith, so that the carriers are thereby conveniently secured from rotation in the guides, and as now considered the saw 49 is provided with a suitable removable handle 51' of any desired or well-known form.

In the present instance the bottom work-guides 14 are each formed with a shoe, as 52, at the free end, which is of suitable depth to cause the upper surface of the guide to rest in a plane above the base 29 of the saw-frame when the guide is brought to a true horizontal position, as indicated by dotted lines in Fig. 2, so that the work will be supported clear of this base. This device is especially adapted for making cuts for simple and complex joints in roof-frames, and from the foregoing it will be understood that by adjusting or tilting the bottom section of the box the work is given the required tilt to cause the saw to pass therethrough at the proper angle to make

- what is termed the "perpendicular" cut when the saw-frame has been adjusted in a horizontal arc, in conformity with the adjustment of said section, to guide the saw at the required angle 5 to make the side cut. Thus it will be seen that the device is capable of making such cuts without first marking the work for the line of cut. Furthermore, the device can be set for use as an ordinary miter-box by simply bringing 10 the bottom work-guides to a horizontal position, and the saw-frame can be adjusted in both a horizontal and vertical arc to guide the saw for angular cuts in making simple and complex joints.
- 15 It will of course be understood that graduations are provided by which the proper setting of the various adjustable parts of the device are determined to make cuts at predetermined angles and that the device is capable 20 of making various forms of cuts without reference to graduations by simply marking the work and adjusting the device properly to cause the saw to pass through the work on these lines.
- 25 An operation of the device to cut a hip-rafter for a roof of one-quarter pitch, for instance, would occur substantially as follows: The bottom work-guides are brought to the required inclination to cause the stick of timbers to 30 rest at the proper pitch, by reference to the graduation-marks 27, for the perpendicular cut, and the saw-frame is then adjusted in the horizontal arc to the proper graduation 45 to bring the saw to the required angle to make 35 the side cut. The timber is then placed in position on the bottom work-guides, with one corner resting against the side work-guides, and the saw is then passed through the timbers. This device is simple of construction, has 40 few parts likely to get out of order, and embodies essential features of adjustability which give it a broad scope of operation.
- Having thus described my invention, what I claim as new, and desire to secure by Letters 45 Patent of the United States of America, is—
1. In a miter-box, the combination with a horizontal base, of a saw-frame pivotally mounted on said base, a plurality of vertical work-guides arranged parallel to the normal 50 vertical axis of the saw-frame, and supporting work-guides connected to the vertical work-guides, and means for adjusting the guides so as to tilt a timber about an axis parallel to the length thereof.
- 55 2. In a miter-box, the combination with a horizontal base, of a saw-frame pivotally mounted on said base, a plurality of work-guides mounted upon the base, and means for adjusting the guides so as to tilt a timber 60 about an axis parallel to the length thereof.
3. In a miter-box, the combination with a horizontal base, of a saw-frame pivotally mounted on the base, a plurality of work-guides supported upon the base, means for 65 adjusting the guides so as to tilt a timber

about an axis parallel to the length thereof, means for varying the vertical axis of the saw-frame, and means for varying the horizontal axis of the saw-frame.

4. In a miter-box; the combination with a 70 base; of a movable work-guiding section comprising a plurality of parallel bars slidably resting at one end on said base, and means to movably support the opposite ends of said bars for vertical adjustment. 75

5. In a miter-box; the combination with a base; of a side work-guiding section movably mounted on said base for vertical adjustment, and a bottom work-guiding section slidably resting on said base and pivotally connected 80 at one side to said side section.

6. In a miter-box; the combination with a base; of a plurality of posts movably mounted on said base for vertical adjustment, and a plurality of horizontally-disposed bars pivotally connected at one end to said posts and 85 slidably resting at the opposite ends on said base.

7. In a miter-box; the combination with a base; of a post movably mounted on said base 90 for vertical adjustment, a laterally-disposed bar pivoted at one end to said post and resting at the opposite end on said base, and means to raise and lower said post.

8. In a miter-box; the combination with a 95 base; of a post movably mounted on said base for vertical adjustment, a rack fixed on the post, a gear engaged with said rack and rotatably supported on said base, and a laterally-disposed bar pivoted at one end to said post and resting at the opposite end on said base. 100

9. In a miter-box; the combination with a base; of a plurality of posts movably mounted on said base for vertical adjustment, racks 105 fixed to the lower portions of the posts, gears meshing with said racks, a horizontally-disposed shaft rotatably supported on said base and carrying said gears, a pawl-and-ratchet contrivance arranged to operate said shaft, 110 and laterally-disposed bars pivotally connected at one end to said posts substantially midway their length and resting at the opposite ends on said base.

10. In a miter-box, the combination with a 115 saw-frame having vertically-disposed guides, of saw-carriers slidably mounted in said guides formed with saw-blade-embracing prongs, oppositely-disposed pins arranged on the inner surfaces of the prongs, and a saw-blade having a longitudinally-disposed pin-engaging groove in one side thereof whereby it is supported and guided by the pins. 120

11. In a miter-box, the combination with a saw-frame having vertically-disposed tubular 125 guides formed with oppositely-disposed blade-receiving slots, of saw-carriers slidably mounted in said guides and formed with prongs having inturned toes, oppositely-disposed pins on the inner side walls of the prongs, and a saw- 130

blade having a longitudinally-disposed pin-engaging groove in one side thereof whereby the said blade may be passed entirely through the work.

- 5 12. An adjustable miter-box, comprising a base, a bracket removably attached to the base at one side, a plurality of posts movably mounted on said bracket for vertical adjustment, racks along the lower portions of the posts, 10 gears meshing with said racks, a shaft rotatably mounted on said bracket and carrying said gears, a pawl-and-ratchet contrivance arranged to rotate said shaft, laterally-disposed bars pivotally connected at one end to said 15 posts midway their length and slidably supported at the opposite end on said base, and a saw-frame pivotally mounted on said bracket for horizontal adjustment and arranged for adjustment on its mounting in a vertical arc. 20 13. In a miter-box; the combination of a base-plate, a saw-frame comprising a horizontally-disposed base-rod, and vertically-disposed guides on said base-rod having blade-receiving slots, a bearing pivotally mounted 25 on said base for adjustment on a vertical axis and adapted to rotatably support said base-rod, a guideway adjacent the outer end of said frame, a steadier for said frame adjustably mounted on said way, posts movably mounted 30 at one side of said base for vertical adjust-

ment, and laterally-disposed bars pivotally connected at one end to said posts and slidably resting at the opposite ends on said base-plate.

14. An adjustable miter-box comprising a base-plate, a bracket having laterally-projecting ears adapted to embrace one edge portion of said plate, a plurality of work-guiding posts movably mounted on said bracket for vertical adjustment, toothed racks along one side of the lower portion of said posts, gears meshing 40 with said racks, a shaft rotatably mounted on said bracket and carrying said gears, a pawl-and-ratchet contrivance arranged to rotate said shaft, laterally-disposed bars pivotally connected at one end to said posts and having 45 shoes at the opposite end resting on said base-plate, a saw-frame comprising a horizontally-disposed base-rod, and vertically-disposed guides on said rod having blade-receiving slots, a bearing for said rod pivotally mounted on 50 said base for adjustment on a vertical axis, a guideway supported on the base-plate adjacent the outer end of said rod, and a steadier for said frame adjustably mounted on said way.

Signed at Seattle, Washington, this 26th 55 day of January, 1903.
